UNITED STATES PATENT OFFICE

HUGH ALEXANDER COULTER, OF WINNIPEG, MANITOBA, CANADA

AUTOMOBILE SIGNAL

Application filed December 1, 1928, Serial No. 323,027, and in Canada November 13, 1928.

The invention relates to improvements in automobile signals and of the type which visibly indicates at the rear of the automobile whether the driver is going to turn in one direction or the other or come to a stop and an object of the invention is to provide a simply constructed, inexpensive and durable device of pleasing design which can be positively relied upon to give the desired signals and which is entirely controlled by the driver at his seat.

A further object is to construct the signal so that it will be plainly visible either by day or night and also such that it normally serves as a tail light and also to illuminate the customary license plate.

A further object of the invention is to provide a signal embodying an outer casing having suitable windows therein and a rotatable drum having the signals thereon and means actuated by suction and controlled within convenient range of the driver's seat for rotating the drum selected amounts to expose desired signals and to provide means for releasing the suction subsequent to giving the signal.

With the above more important and other minor objects in view which will become more apparent as the description proceeds, the invention consists essentially in the arrangement and construction of parts hereinafter more particularly described, reference being had to the accompanying drawing, in which:

Fig. 1 is a rear view of the signal.

Fig. 2 is an enlarged vertical cross sectional view through the signal at 2—2' Figure 1.

Fig. 3 is an enlarged vertical cross sectional view through the signal at 3—3' Figure 1.

Fig. 4 is a horizontal central sectional view centrally through the signal at 4—4' Figure 3.

Fig. 5 is a vertical sectional view through the valve employed on the dash, certain parts being shown in side elevation.

Fig. 6 is a sectional view at 6—6' Figure 5 and looking towards the base of the valve.

Fig. 7 is an inverted view of the valve disc.

Fig. 8 is a plan view of the drum forming signalling sheet shown in reduced scale.

In the drawing like characters of reference indicate corresponding parts in the several figures.

The casing 1 of the signal is in the form of a cylindrical metallic box, the body thereof being provided at the rear with a window or sight opening 2 and at the under side with a window 3. One end of the casing is closed by a cap 4 to which I have secured centrally a lamp socket 5 of the conventional form which projects into the casing as shown to form a bearing for the adjacent end of the drum later described.

On the other end of the casing, I mount a collar or band 6 which carries an internal cross partition 7 closing the end of the casing and the outer end of the collar is closed by a cap 8. The collar and the former cap can be frictionally applied sufficiently tight to hold them in place or can be otherwise releasably fastened. The band contains the actuating parts for the drum later described.

Between the cap 4 and the cross partition and within the casing, I locate a rotary drum which is formed from a flanged disc-like head 9 rotatably mounted on the inner end of the lamp socket, a flanged disc-like head 10 carrying centrally a stud shaft 11 rotatably mounted in the partition and a cylindrical shell 12 suitably attached to the flanges of the heads as by friction rings 13. The shell has the desired signals thereon and the signals are adapted to appear successively through the rear window of the casing when the drum is turned.

I have found that a good quality paper such as bristol board can be used for the shell and the paper will all be blackened such as by inking with the exception of the direction signals, stop and tail light signals, the latter being coloured red while the former are white so that when a lamp illuminates the interior of the drum, the stop and direction signals will appear in white letters while the tail light signal will show red.

The arrangement of the signals as they appear on the sheet is as shown in Figure 8, the tail light signal being indicated at 14 and the other signals as shown and consisting of the

words "Right", "Left" and "Stop" in the order named.

To the stub shaft I secure by a pin 15', a pinion 15 and the pinion meshes continuously with a rack 16 formed at the periphery of a segmental plate 17 which is pivotally mounted on a pivot pin 18 fastened to the partition. One end of the rack is normally held engaged with a stop pin 19 secured to the partition by the action of a coiled spring 20 fastened to the segmental plate and to a lug 21 secured to the partition. When the rack is engaged with the stop, the tail light signal 14 is visible through the rear window and the other signals are non-visible. The illuminating lamp 22 is mounted in the socket in the usual way within the drum and will be used at night to illuminate the various signals and in this connection I might remark that there will always be sufficient light passing through the signals of the drum to illuminate the customary license plate positioned adjoining the under window.

In order to actuate the drum, I utilize the suction of the automobile engine and control it by a valve positioned within convenient range of the driver's seat.

A cylinder block 23 is secured permanently to the partition and projects through the collar and is herein shown as bored to provide three cylinders of varying length and indicated by the reference numerals 24, 25 and 26, the cylinder 24 being the longest and 26 the shortest. Within the cylinders, I mount plungers or pistons 24', 25' and 26' and to the pistons I pivotally connect the ends of three slotted links 27, 28 and 29 having the slots thereof of varying length as shown.

A lever arm 30 is permanently secured to the rack bar and crosses the links and is connected slidably to the several links by pins 31, 32 and 33 entering the link slots. The outer ends of the pins are provided with enlarged heads to prevent the links escaping. To the cylinders, I lead suction pipes 34, 35 and 36 and these pass to the stationary base plate of a controlling valve located within convenient range of the driver's seat such as on the dash of the automobile.

The controlling valve embodies a stationary base plate 37 and a rotating disc 38, the base plate being suitably fastened to the dash and being provided with a central opening 39 through which a bolt 40 passes, the one end of the bolt being screw threaded or otherwise firmly fastened to the disc and the other end being provided with a head 41. A hole 42 is formed in the dash to receive the screw and the pipes 34, 35 and 36 and a coiled spring 40' is placed on the screw between the base plate and the head and normally holds the disc pressed tight against the base plate but permits of rotation of the disc in respect to the plate.

A pipe 43 communicates with a port 44 in

the base plate and this pipe leads to say the intake manifold 45 of an automobile engine. I provide also three other ports 46, 47, and 48 in the base plate, such ports being concentric to the bolt and communicating with the pipes 34, 35 and 36. The disc 38 is provided on the under side with a circular slot 49 which is adapted to be at all times in communication with the port 44 of the base plate and the slot is provided with an offset duct 50 which is adapted in the rotation of the disc to sweep over the base plate and register with one or the other of the ports 46, 47 and 48.

The disc is provided also with a further series of equally spaced ports 51 and the arrangement is such that when the offset 50 is in communication with a selected port, say that 46, the other two ports 47 and 48 are open to atmosphere through certain of the holes 51 registering therewith. The disc is provided opposite the offset 50 with a pointer 52 and with a manipulating handle 53 and the base plate is provided with graduation marks radially opposite the ports 46, 44, 47 and 48 and the graduation marks have the letters "L," "N," "R" and "S" associated therewith, such letters indicating left, neutral, right and stop respectively and the arrangement is such that when the pointer is opposite any one of the graduation marks, the signal corresponding to that graduation indication will be indicated.

Normally the signal remains with the tail light signal appearing through the rear window and at such time, the handle is set so that the pointer is opposite the letter "N" on the base plate and the suction pipe 43 is not connected to any port leading to the cylinder block of the signal. If the driver desires to turn to the right, he will turn the handle to bring the pointer opposite the letter "R" on the base plate at which time the suction pipe 43 is connected through the port 44, slot 49, offset 50 and port 47 with the pipe 36 leading to the cylinder 26. There is accordingly an instantaneous indrawing of the piston 26' for the full length of the cylinder 26 which effects through the link the pulling of the lever arm 30 a distance designed to rotate through the intermeshed rack and pinion, the drum a sufficient portion of a revolution to bring the signal "Right" centered within the rear window. Similarly the setting of the indicating pointer with the letters "L" or "S" on the base plate, will actuate the pistons 25' and 24' respectively to cause the rotation of the drum a proper amount to centre the signals "Left" or "Stop" in the rear window.

In this connection I wish it to be noticed that the distance which the lever arm is swung is controlled by the length of the respective cylinders, the piston travelling in each case the full length of its containing cylinder acting under the suction of the engine cylinder.

Further it will be noted that when any link is being actuated, the remaining links have no end movement but simply swing on their pivotal connection to the piston to accommodate the movement of the lever as actuated by the working link. It will be observed that the collar 6 is formed with an offset 54 and this is provided to accommodate the outer end of the long link 29 when the link 27 is working.

Whilst I have described the drum as actuated by the suction of the engine, I wish it to be understood that it could also be operated by air or other fluid under pressure at which time, the structure would have to be slightly modified by having the spring 20 pulling the rack in the reverse direction to hold the pistons at their innermost ends of the cylinders and varying the slots of the links accordingly and reversing the position of the signals on the signalling drum. That is to say, the words "Right," "Left" and "Stop" instead of appearing above the tail light signal 14 as in Figure 4, would appear there below and in the order named. Obviously by adding further actuating pistons, links and connections, it would be possible to place other signalling material on the drum and while I have indicated the signals by words, it will be readily understood that they might be otherwise indicated as custom might demand.

What I claim as my invention is:—

1. In an automobile signalling device, a stationary casing having a rear window therein, a cylindrical drum rotatably mounted within the casing and having a plurality of signalling symbols thereon selectively visible in the rotation of the drum through the window, a plurality of air cylinders and pistons operating therein, an operating connection between each piston and the drum designed to effect a rotary movement of the drum upon any piston being actuated, means limiting the length of stroke of the pistons, each piston having a different length of stroke and gauged such that the symbols will be separately exposed through the rear window by selectively actuating the pistons and valve controlled means for selectively exhausting the air from any cylinder.

2. In an automobile signalling device, a stationary casing having a rear window therein, a cylindrical drum rotatably mounted within the casing and having a plurality of signalling symbols thereon selectively visible in the rotation of the drum through the window, a plurality of air cylinders of varying length carried by one end of the casing and located adjoining one end of the drum, a pinion secured to the drum, a pivoted segmental rack bar meshed with the pinion, a spring attached to the casing and the rack bar, a stop pin engaging the rack bar and co-operating with the spring to retain the

drum normally in a non-signalling position, a plurality of pistons operatively mounted within the cylinders, a lever arm secured to the rack bar, pins carried by the lever arm, pulling links pivotally secured to the pistons and longitudinally slotted to slidably receive the several pins aforesaid and valve controlled means for selectively exhausting the air from any cylinder to effect the movement of the piston therein and the consequent rotation of the drum, the length of the cylinder controlling the movement of the piston and the length of stroke of the piston being adapted to rotate the drum a predetermined distance to bring a selected signalling symbol into view through the window.

3. In an automobile signalling device, a stationary casing having a rear window therein, a cylindrical drum rotatably mounted within the casing and having a plurality of signalling symbols thereon selectively visible in the rotation of the drum through the window, a plurality of air cylinders and pistons operating therein, an operating connection between each piston and the drum designed to effect a rotary movement of the drum upon any piston being actuated, means limiting the length of stroke of the pistons, each piston having a different length of stroke and gauged such that the symbols will be separately exposed through the rear window by selectively actuating the pistons, valve controlled means for selectively exhausting the air from any cylinder and a tension spring for returning the drum to its original position.

Signed at Winnipeg, this 18th day of September, 1928.

HUGH ALEXANDER COULTER.
